UNITED STATES PATENT OFFICE.

GEORGE B. AMBLER, OF LEOMINSTER, MASSACHUSETTS, ASSIGNOR TO F. A. WHITNEY CARRIAGE COMPANY, OF LEOMINSTER, MASSACHUSETTS, A CORPORATION OF MASSACHUSETTS.

LOOM.

Application filed February 24, 1927. Serial No. 170,493.

This invention relates to looms and in particular to looms for weaving relatively bulky or stiff material which is not well adapted for handling by the ordinary missile shuttle. As an example of such material I may mention so-called fiber or artificial reed fabrics which are extensively used in the manufacture of baby carriages and furniture. The loom which I here disclose as an example of my invention is in some respects similar to that disclosed in the patent to Arrouquier 618,820, Feb. 7, 1889, and from one point of view may be considered as an improvement on a loom of the type shown in that patent and one providing for particularly rapid and accurate weaving.

My invention will be well understood by reference to the following description of an illustrative embodiment thereof, such parts as are necessary for an understanding thereof being shown in the accompanying drawings, wherein:

Fig. 1 is a fragmentary and broken front elevation of the loom reed and the feeding means for the filling strand;

Fig. 2 is a section on the line 2—2 of Fig. 1 on a larger scale;

Fig. 3 is a fragmentary end elevation of the filling feeding means and various driving trains;

Fig. 4 is an enlarged vertical section through one of the reed dents and cooperating parts; and

Fig. 5 is a horizontal section showing a detail to be referred to.

In the accompanying drawings I have shown only so much of a loom mechanism as is necessary to provide a clear understanding of the invention. It will be understood that the warps are led from suitable let-off mechanism and pass through the reed about to be described, and that the finished fabric may pass over a breast beam to suitable take-up mechanism. Any suitable shedding means, as, for instance, harnesses, are employed to form a shed as indicated in Fig. 2. All these parts may be of any suitable or conventional character and it is not necessary here to illustrate them.

Referring now to Figs. 1 and 2 of the drawings, I have there shown a suitable reed 7 having a series of upstanding dents 9 between which pass the warps and which are adapted to beat up the filling. The reed is reciprocated and preferably is arranged to

move rectilinearly, herein being shown as sliding at its ends on the frames 11 at the sides of the loom and guided thereon by suitable gibbs 13. The reciprocating motion of the reed is preferably incessant. In other words, while, of course, in the example shown the reed comes to a dead stop at its forward and rearmost positions respectively, there is no dwell or cessation of motion during which time the pick takes place. Thus, for example, eccentrics 15 on shaft 17 may move the reed incessantly with a simple harmonic motion. Among other advantages of this construction it may be noted that as the reed moves forward toward the fell of the cloth to beat up the filling, while the motion as a whole may be rapid, it is relatively slow at this portion of the cycle so that the filling is pushed powerfully and gently into the fell of the cloth without danger of its being thrown too far or of its rebounding.

Referring now to Fig. 1, the end of the filling strand *f* is projected forward in a manner hereinafter more fully to be described by means of one or more pairs of feed rolls (two being here shown) which may embody an upper driven roll 19 and a cooperating lower driven roll 21, these rolls being mounted at the side of the loom in a fixed position as regards the motion of the reed. Suitable guiding means on the reed, herein shown as fingers 23 cooperating with the dents 9, receive the end of the strand and prevent it from buckling or twisting and guide it through the shed to provide a pick or shot of filling. The fingers 23 (see Fig. 4) are here shown as grooved adjacent their lower ends along one side thereof as indicated at 25, these grooved side portions being presented to the dents 9 of the loom while the filling is being inserted to form guide eyes and the grooves may be somewhat flared on the receiving side as shown to facilitate the passage of the strand therethrough. As the reed moves to its forward position, toward the right in Fig. 2, the fingers 23 may be swung to the dotted line position of Fig. 2 to release the pick of filling which is deposited therefrom and beaten up by the dents 9 into the fell of the cloth. Then as the reed retreats, the fingers are closed again to the full line position of Fig. 2 or the position of Fig. 4 ready to receive the new pick of filling.

To operate the fingers 23 I have herein shown a rock shaft 25 mounted on brackets 27 at either end of the reed and paralleling the same. The fingers 23 are provided with hub-like portions 29 embracing the shaft 25 and may be secured individually in adjusted position thereon by means of set screws 31. Preferably the shaft 25 is grooved out, as indicated at 33, and set screws 31 tapping through the hub rest against the upwardly facing wall of this groove and are secured in position by lock nuts 35. Suitable springs may be provided to hold the set screws against the wall of the groove 33 and I have herein shown the main body of each finger as cored out to accommodate helical spring 37, a suitable cross-bar 39 being provided for securing one end of the spring while the other may be detachably hooked to pin 41 projecting from the forward face of the corresponding reed dent 9. The arrangement shown permits individual adjustment of the fingers relatively to the shaft so that the grooved ends thereof close snugly against the cooperating faces of the reed dents. The construction is also such that the spring 37 may be unhooked and the entire finger swung counterclockwise, viewing Figs. 2 or 4, out of the way. Thus, for instance, if it were desired to weave a narrower fabric on a loom of given construction some of the fingers at the right of the reed, viewing Fig. 2, could be thus temporarily thrown out of operation.

The rock shaft 25 is actuated during the forward portion of the travel of the reed and I have herein shown lever arms 43 extending upwardly from the ends thereof and carrying cam followers 45 working in the cam slots 47 in plates 49 bolted to the loom sides. It will be apparent from Fig. 2 that as the reed moves forward from the full line position shown, the follower 45 will strike the forward vertical wall of the slot and travel downwardly in contact therewith, rocking the shaft and swinging the fingers 23 to the dotted line position shown, thus releasing the strand of filling which is beaten up into the fell of the cloth by the dents 9.

The feeding rolls previously referred to are driven in accurately timed relation to the movement of the reed, the shaft 17 which reciprocates the latter herein being shown as taking its motion through the bevel gears 51 and a gear train 53 from a power shaft 55. This power shaft 55 through a gear train 57 may drive counter-shaft 59 to which is geared the shaft 61 of the feed roll 19 and also, through a universal joint 63, the shaft 65 of the feed roll 21, this shaft being mounted in a sliding box 67 to permit the roll 21 either to be pressed upwardly toward the roll 19 to pinch the filling strand *f* between them and feed the same forwardly or to be dropped downward-

ly to interrupt the feeding of the strand. This motion is effected by suitable edge cams 69 cooperating with suitable follower surfaces on the sliding boxes 67 to reciprocate the latter and the shafts of these cams 69 are herein shown as driven through a suitable train 70 including a driving gear 72 which is in effect formed as a part of the hub of one of the bevel gears 51. The shafts of cams 69 and the eccentric shaft 17 are thus operated in accurately timed relation.

The cycle of operation is such that, assuming the reed in the position of Fig. 2 and moving rearwardly or toward the left, the harnesses have operated to change the shed and the fingers 23 have swung downwardly to the full line position to present a series of guiding eyes throughout the length of the reed. The cams 69 then raise the lower feed rolls 21 which grip the filling and start feeding it forwardly through these eyes and this motion may continue during the retreating movement of the reed and during the first part of its forward movement, the reed not being stopped while the pick of filling is inserted. The length of time during which this feeding action is carried on and its speed will depend to some extent upon the width of the fabric being woven. The cams then permit the rolls 21 to be moved downwardly to interrupt this feeding movement, the filling, which preferably has been drawn forward from a large supply coil, is severed at the intake side of the reed and as the reed moves forward the fingers 23 are swung to the dotted line position of Fig. 2, releasing the pick of filling which is beaten up into the fell of the cloth as the reed reaches its forward center position. The cutter for severing the filling is preferably located on the reed and I have herein indicated at 71 (Fig. 1) its position at the inner side of an apertured upright 73 at the end of the reed nearer the feed rolls. As the particular construction of this cutter forms no part of the invention herein claimed and as it may take widely varying forms, I have deemed it unnecessary to illustrate it in detail. It may, if desired, be operated in the forward part of the reed movement by means similar to those utilized for operating rock shaft 25.

In the preferred embodiment of the invention shown the feed rolls are stationary at the side of the loom while the reed reciprocates constantly and I preferably provide means for carrying or guiding the strand between the rolls and the reed. I have herein shown (see Fig. 5) a swinging guide 75, conveniently in the form of a tube fitting the filling sufficiently close to prevent any buckling of the same, interposed between a fixed guide 77 at the bite of the feed rolls and the apertured upright 73 at the end of the reed having an opening in alignment with the eyes thereon. The guide

tube 75 is mounted to swing in a horizontal plane as the reed reciprocates and for this purpose one of the elements between which it extends, herein the fixed guide 77 adjacent the feed rolls, is recessed or socketed and the end of tube 75 works therein in a manner somewhat like a ball and socket joint. The opposite end of the tube may be provided with a shoulder 79 while the 10 upright 73 on the reed has an opposing shoulder 81 and about these shoulders is placed a helical compression spring 83 which suspends the right hand end of the tube, holds the left hand end (see Fig. 5) seated in the socket on guide 77 and permits a swinging movement thereof as indicated by the dotted line in Fig. 5. The construction also permits the ready removal of the guide tube which is of considerable 20 advantage in the case of any stoppage or breakage of the filling. To permit it to be removed it need only be pressed toward the right in Fig. 5, compressing spring 83 until the left hand end is freed from the socket 25 in which it works, and the tube may then be lifted out.

I have described in detail the particular embodiment of my invention shown by way of example in the accompanying drawings. 30 The detailed character of the description has had for its object to make clear what is there shown and it is not to be understood as definitive of or limiting the scope of the invention. Obviously the construction 35 might be widely varied without departing from the spirit of the invention.

What I claim as new and desire to secure by Letters Patent I shall express in the following claims.

40 1. In a loom, in combination, a reed reciprocating with an incessant uniform motion, elements cooperating with reed dents to provide guide eyes for a shot of filling, means for moving said elements to open the eyes to release the filling at about the forward position of the reed, and feeding means for a filling strand located at the loom side and relatively stationary as regards the movement of the reed, operating 45 intermittently on the filling to feed the same during a part of the motion of the reed while said eyes are closed and in itself by said operation effective to traverse the filling completely across the fabric.

55 2. In a loom, in combination, a reed reciprocating with an incessant uniform motion, elements cooperating with reed dents to provide guide eyes for a shot of filling, means for moving said elements to open the eyes to release the filling at about the forward position of the reed, feeding means for a filling strand located at the loom side and relatively stationary as regards the movement of the reed, operating intermittently on the filling to feed the same during

a part of the motion of the reed while said eyes are closed and in itself by said operation effective to traverse the filling completely across the fabric, and a device interposed between said feeding means and the reed adapted to maintain a continuous guiding control of the filling between said elements during its projection.

3. In a loom, in combination, an incessantly reciprocating reed, elements cooperating with reed dents to provide guide eyes for a shot of filling, means for moving said elements to open said eyes to release the filling at the forward position of the reed, means at the loom side for projecting a filling strand through the eyes operating intermittently thereon during a part of the motion of the reed while said eyes are closed, and a swinging guide for the filling strand connecting said means and the reed.

4. In a loom, in combination, an incessantly rectilinearly reciprocating reed, elements cooperating with reed dents to provide guide eyes for the filling strand, means for moving said elements to open said eyes to release the filling at about the forward position of the reed, means at the loom side for projecting a filling strand in the plane in which the eyes move, a swinging guide for the strand interposed between said projecting means and the reed and means for operating the projecting means during a part of the motion of the reed while said eyes are closed.

5. In a loom of the class described a reciprocating reed, a rock shaft extending therealong, fingers carried by the rock shaft having recessed portions opposing the dents of the reed, an arm on the shaft and a fixed cam adjacent the reed cooperating with said arm.

6. In a loom of the class described a reciprocating reed, a rock shaft extending therealong, fingers individually adjustable angularly about the shaft having recessed portions opposing the dents of the reed, an arm on the shaft and a fixed cam adjacent the reed cooperating with said arm.

7. In a loom of the class described a reciprocating reed, a rock shaft extending therealong, fingers having recessed portions cooperating with the dents of the reed and engaged with said rock shaft to be lifted thereby away from said dents and normally individually spring pressed toward the same and means for intermittently rocking the shaft.

8. In a loom of the class described a reciprocating reed, a rock shaft extending therealong, fingers having recessed portions cooperating with the dents of the reed, set screws adjustably engaging the fingers individually with the shaft to be lifted thereby away from the dents, said fingers being normally spring pressed toward the same, and

means for intermittently rocking the shaft.

9. In a loom of the class described a reciprocating reed, a rock shaft extending therealong, fingers having hubs on the rock shaft, set screws engaging said hubs individually therewith, said fingers having recessed portions cooperating with the dents of the reed and means for intermittently rocking the shaft.

10. In a loom, in combination with a reciprocating reed which provides a guideway through the shed for supporting the filling during its insertion and including a guide at one end of the reed, means at the loom side for feeding the filling strand including a guide through which the filling passes, and a pivotally mounted guide tube between said guides.

11. In a loom, in combination with a reciprocating reed which provides a guideway through the shed for supporting the filling during its insertion and including a guide at one end of the reed, means at the loom side for feeding the filling strand including a guide through which the filling passes, and a removable guide tube extending between said guides and connected thereto for swinging movement, the connection at one end comprising a spring.

12. In a loom, in combination with a reciprocating reed which provides a guideway through the shed for supporting the filling during its insertion and including a guide at one end of the reed, means at the loom side for feeding the filling strand including a guide through which the filling passes, one of said guides having a socket and the other a shoulder, a tube having one end working in the socket and at the other end a cooperating shoulder and a compression spring between the shoulders.

13. In a loom, in combination with means providing a guideway through the shed for supporting the filling during its insertion, the feeding means for the filling comprising cooperating feed wheels therefor, one of said wheels being mounted in a sliding box, means for synchronously rotating said wheels including a universal joint to said one wheel, and a cam for reciprocating said box.

14. The filling guiding element having a

hub and an extension therefrom provided at its end with a groove along one side, the intermediate portion being cored out to accommodate a spring and having provision for anchoring an end of the spring.

15. In a loom, in combination, an incessantly reciprocating reed, elements cooperating with reed dents to provide guide eyes for a shot of filling, means for moving said elements to open said eyes to release the filling at the forward position of the reed, means at the loom side for projecting a filling strand through the eyes operating intermittently thereon during a part of the motion of the reed while said eyes are closed, a member carried by the reed at the end thereof adjacent the projecting means through which the filling passes and means for severing the filling inwardly of said member.

16. In a loom, in combination, an incessantly reciprocating reed, elements cooperating with reed dents to provide guide eyes for a shot of filling, means for moving said elements to open said eyes to release the filling at the forward position of the reed, means at the loom side for projecting a filling strand through the eyes operating intermittently thereon during a part of the motion of the reed while said eyes are closed, a member on the end of the reed adjacent the projecting means through which the filling passes, a device providing a continuously effective guide between said means and said member and means for severing the filling inwardly of said member.

17. In a loom, in combination, a reciprocating reed, elements cooperating with reed dents to provide guide eyes for a shot of filling, means for moving said elements to open said eyes to release the filling at the forward position of the reed, means at the loom side for projecting the end of a filling strand through said eyes while they are closed, a member carried by the reed at the end thereof adjacent the projecting means through which the filling passes and means for severing the filling inwardly of said member.

In testimony whereof, I have signed my name to this specification.

GEORGE B. AMBLER.
